SHOE CONSTRUCTION FOR RUBBING MACHINES

Peter T. Triolo, Rockford, Ill., assignor to Sundstrand Machine Tool Co., a corporation of Illinois

Application July 14, 1950, Serial No. 173,798

10 Claims. (Cl. 51—189)

1

This invention relates to rubbing machines, and more particularly to a demountable rubbing shoe for use with a reciprocatory rubbing machine.

It is the general object of this invention to provide a new and improved demountable shoe for use with a rubbing machine.

It is a more specific object of this invention to produce a demountable shoe for use with a rubbing machine having a reciprocatory member such as the rubbing machine shown in the application of Peter T. Triolo and Ray W. Erickson filed on March 1, 1950, as Serial No. 147,638.

It is a further object of this invention to produce a demountable shoe for use with a rubbing machine of the type described in the preceding paragraphs which may be quickly and easily secured to the rubbing machine and which may be removed and replaced with little waste motion or time.

Yet another object of this invention is to produce a demountable shoe member for use with a rubbing machine having a reciprocatory member and to provide the members with readily releasable locking means to permit the members to be firmly locked together during operation of the machine and yet to permit the shoe member to be removed from the reciprocatory member by a simple rapid operation.

Another object of the invention is to produce a demountable shoe which is substantially rectangular in shape and is provided adjacent one end with a pair of upstanding lugs adapted to be received in complementary slots in a reciprocatory member, each of which lugs is provided with a wedging face facing the other end of the shoe, there being a dovetail recess at the other end of the shoe adapted to receive a complementary dovetail on the member, and to provide such a machine with clamping means to clamp the shoe against the member whereby the wedging faces of the lugs force the dovetail into the recess, thus producing a firm union between the member and the shoe and yet one which may be readily released by releasing the clamping means.

Other and further objects of the invention will be readily apparent from the following description and drawings, in which:

Fig. 1 is a side elevation of the lower portion of a rubbing machine embodying the invention partially broken away to various depths more clearly to illustrate the invention;

Fig. 2 is a side elevation of the left-hand portion of the apparatus shown in Fig. 1 and showing the relative positions of the machine and the

2

demountable shoe of this invention during the separating or engaging operation;

Fig. 3 is an elevational view of the left-hand end of Fig. 1;

Fig. 4 is a view of the bottom of the reciprocatory member, and

Fig. 5 is a plan view of the top of the demountable shoe, Figs. 4 and 5 being so arranged as to position the reciprocatory member and the demountable shoe so that rotation of the shoe 180° about its longitudinal axis will place it in position to be attached to the bottom of the reciprocatory member.

While the invention is susceptible of embodiment in many different forms, there is shown in the drawings and described in detail one specific embodiment, with the understanding that the present disclosure is to be considered as an exemplification of the principles of the invention and is not intended to limit the invention to the embodiment illustrated. The scope of the invention will be pointed out in the appended claims.

When using rubbing machines equipped with an abrasive material, such as sandpaper, it is clear that such material will wear in a comparatively short period of time, whereupon the removal of the worn out material and the fitting and insertion of new paper become necessary. This operation can be a time-consuming one.

With the shoe of this invention it is possible for the workman to use a number of shoes to which sheets of abrasive have previously been attached. When the abrasive becomes worn on any one shoe, it is merely necessary to flip the clamping handle on the machine whereupon the shoe presently in use will drop off. It is then but a matter of moments to slip a new shoe in place, flip the clamping means and the workman is ready to continue with his work. When the rubbing machine is used in filing operations, file sections may be secured to the bottom of the shoes, with different shoes carrying file sections of different fineness, and changes in shoes may be made in a like manner. Thus it is possible to effect a considerable time saving by the use of readily demountable shoes.

According to this invention, there is produced a demountable shoe which can readily be removed and replaced with a shoe of similar construction in a much shorter space of time than is necessary to replace the abrasive material itself.

For the purpose of exemplary disclosure, the demountable shoe construction of this invention is shown in the drawings and will hereinafter be described as employed with a rubbing machine

of the general type disclosed in the aforementioned application of Peter T. Triolo and Ray W. Erickson. As shown in that application, the rubbing machine comprises a hollow body member 20, to the lower portion of which a reciprocatory member 21 is attached and adapted to be driven by an air motor enclosed in the body member.

As contrasted with the apparatus shown in the above mentioned pending application, the reciprocatory member illustrated in the drawings does not carry the rubbing material but is so formed as to receive a demountable shoe member 22 which may be provided with a rubber pad 23 to provide a resilient backing for a sheet of abrasive material 24 held to the shoe member 22 by the clamping means 25 provided at each end of the shoe.

As best seen in Figs. 1 and 3, the body is provided with a channel member 26 having inturned bottom flanges 27 extending along each side of the body and on which wheels 28 mounted on the reciprocatory member 21 may roll. The reciprocatory member is provided with flange portions 29 which underlie the flanges 27 more securely to hold the reciprocatory member in position.

As best seen in Fig. 4 a drive shaft 30 is rotatably mounted in the body member and adapted to be driven by a motor enclosed therein. Secured to the drive member are a pair of oppositely facing eccentrics 31 and 32. A connecting rod 33 is secured to the eccentric 31 and is attached to a counterweight 34 slidably mounted in the channel members 26. A second connecting rod 35 is secured to the eccentric 32 and to the reciprocatory member to reciprocate the member.

In order to provide for the attachment of the shoe member 22 to the reciprocatory member, the latter is provided with a pair of slots 36 and 37 adjacent one end thereof, the slot 36 being provided with parallel sides 38 and 39 which extend angularly outwardly from the central portion of the member. Thus the slot 36, as defined by the sides 38 and 39, extends outwardly at an angle of less than 90° (and more than 0°) relative to the direction of reciprocation of the member and thus relative to the longitudinal axis of the member. The slot 37 is similarly provided with the sides 40 and 41 which extend outwardly at a similar angle. At the opposite end of the reciprocatory member 21 there is provided a fitting in the form of a dovetail 42 which extends arcuately outwardly from the member 21.

Referring now to Fig. 5, the shoe 22 comprises a flat plate 44, generally rectangular in shape, at one end of which there is provided a pair of parallelogram-shaped upstanding lugs 45 and 46. The lugs are substantially complementary in shape to the slots 36 and 37 and the faces 47 and 48 of each of the lugs facing the other end of the shoe are wedge shaped. If desired, the sides of the slots 36 and 37 against which the wedge surfaces 47 and 48 are to bear may also be wedge shaped, although it has been found that this is generally not necessary. It will be noted that the sides 47 and 48, and the sides 47a and 48a opposite thereto on each lug extend diagonally outwardly relative to the axis of reciprocation of the shoe. A plate 50 is located at the other end of the shoe and firmly secured thereto. The plate is provided with an arcuate edge 51 matching the edge of the dovetail 42 and also with an undercut portion 52 complementary to a wedge portion 53 formed along the edge of the dovetail.

A pair of spaced brackets 55 and 56 are secured

to the plate 44 at the lug carrying end of the shoe and support a clamp engaging means in the form of a rod 57. The rod 57 is adapted to be engaged by a hook portion 58 (Fig. 2) of a catch 59 attached to the reciprocatory member. In order to force the catch 59 upwardly to bring the shoe member into close engagement with the reciprocatory member there is provided a lever 60 having a handle portion 61 and rotatably mounted on a shaft 62 carried in brackets 63 and 64 at one end of the reciprocatory member. The lever 60 carries cam portions 65 adapted to engage the underside of the catch 59 when the handle is swung upwardly (clockwise) from the position shown in Fig. 2 to the position shown in Fig. 1. To retain the catch in position there is secured thereto a bracket 66 having a slot 67 through which the shaft 62 extends. Thus the catch is loosely mounted on the reciprocatory member and is free to move in the slot 67 upwardly and downwardly with pivotal movement of the lever 60. The central portion 68 of the outer end of the catch 59 is bent inwardly as shown in Figs. 2 and 3 to engage a shaft 69 secured to the twin side pieces 69a and 69b forming a portion of the lever 60. The purpose of this arrangement is to limit the forward or counterclockwise movement of the lever 60 when the clamp is disengaged.

To mount the shoe on the reciprocatory member it is merely necessary to rotate the shoe 180° from the position shown in Fig. 5 to bring its face into contact with the bottom of the reciprocatory member shown in Fig. 4. The wedge face 53 of the dovetail 42 may then be inserted into the undercut portion 52 of the plate 50. This will bring the two members to the relative position shown in Fig. 2. The shoe may then be swung upwardly about the engaged dovetail and plate as a pivot until the lugs 45 and 46 enter the slots 37 and 36 respectively. At this point the hook portion 58 of the catch 59 will be adjacent to and just under the rod 57. By swinging the handle 61 upwardly the hook engages the rod to force the shoe upwardly against the bottom of the reciprocatory member. The sides 38 and 40 of the slots 36 and 37 engage the wedge faces 48 and 47 respectively of the lugs to shift the shoe slightly to the left as shown in Fig. 1 to wedge the slanting face 53 of the dovetail into the portion 52. This wedging action provides a very firm fit or union between the shoe and the reciprocatory member. Longitudinal slippage between the parts is prevented by the dual wedging action of the wedge faces 47 and 48 on the lugs and the wedge faces 52 and 53 on the dovetail and plate. In addition, the angular arrangement of the lugs and slots prevents transverse slippage between the parts.

It is, of course, clear that various types of rubbing material may be secured to the shoe 22. Thus for a filing operation, file sections may be formed integral with the shoe, or separate file sections may be screwed, bolted or otherwise secured to the outer side of the plate 44. If abrasive material, such as sandpaper or emery paper is to be used, the clamping means 25 is used for clamping a sheet of such material thereto.

As can best be seen in Figs. 1 and 3, a pair of clamps 70 and 71 are provided at each end of the shoe 22 with each clamp having a clamping face portion 72 which extends transversely substantially the entire width of the shoe and is adapted to press the sheet of abrasive material

24 into frictional engagement with a recess 14 provided at each end of the shoe. The clamps 10 are rotatably and removably mounted about the pins 15 (Fig. 5) mounted in pairs of brackets 16 fixed to the plate 44. One such pair of brackets is provided at each end of the shoe. Each clamp is provided at each end with a pair of parallel lever arms 17 which extend inwardly and downwardly therefrom as shown in Fig. 1. The inner arm of each pair of lever arms 17 is provided with a slot 17a which receives the pins 15. Stretched between the pairs of lever arms at opposite ends of the shoe is a resilient device such as a thick elastic band 18, the bands extending along each side of the shoe as shown in Fig. 5. The ends of the band are formed with a rounded portion 19 and a pin 20 extends through a hole in the rounded portion of the band and through matching openings in each pair of lever arms. Each clamp is provided with a pair of finger actuating portions 21 to rotate the clamp about the rod 15 to lift the portion 12 away from the recess 14 as shown in the left-hand side of Fig. 1 to permit the insertion of the ends of the abrasive material 24 therebetween. Upon release of the finger pressure the tension of the bands 18 brings the clamping edge 12 of the clamp firmly against the abrasive material, as shown in the right-hand portion of Fig. 1, to hold it snugly in the recess.

I claim:

1. In a rubbing machine having a reciprocating member, demountable rubbing means to be reciprocated by the member comprising a substantially rectangular shoe a pair of parallelogram-shaped lugs upstanding from the shoe adjacent one end thereof, each of said lugs having two sides extending substantially diagonally of the axis of reciprocation of the shoe, with the side toward the other end of the shoe having a wedge face, a pair of complementary slots in the reciprocating member adapted to receive the lugs, a plate defining an arcuate dovetail recess at said other end of the shoe, a complementary dovetail on the reciprocating member adapted to be inserted in the recess, clamp engaging means on the shoe, and a clamp carried by the reciprocating member adapted to engage the clamp engaging means to force the lugs into the slots to wedge the dovetail in the recess.

2. In a rubbing machine having a reciprocating member, demountable rubbing means comprising a shoe member, a pair of lugs on the shoe member adjacent one end thereof, each of said lugs being provided with a wedging face, complementary slots adjacent one end of the reciprocating member adapted to receive the lugs, a dovetail on the reciprocating member adjacent the other end thereof, a complementary dovetail recess on the shoe member adjacent the other end thereof and adapted to receive the dovetail, and lever means carried by one member and adapted to engage the other member to force the lugs into the slots to wedge the dovetail in the recess.

3. In a rubbing machine having a reciprocating member, demountable rubbing means comprising a shoe member, a pair of lugs on one member adjacent one end thereof, each of said lugs being provided with a wedging face, complementary slots adjacent one end of the other member and adapted to receive the lugs, a dovetail on one member adjacent the other end thereof, a complementary dovetail recess on the other member adjacent the other end thereof and adapted to receive the dovetail, and lever means

carried by one member and adapted to engage the other member to force the lugs into the slots to wedge the dovetail in the recess.

4. In a rubbing machine having a reciprocating member, demountable rubbing means comprising a shoe member, a lug on one member having a wedging face, a complementary slot on the other member adapted to receive the lug, a dovetail on one member, a complementary dovetail recess on the other member adapted to receive the dovetail, and lever means carried by one member and adapted to engage the other member to force the lug into the slot to wedge the dovetail in the recess.

5. In a rubbing machine having a reciprocating member, demountable rubbing means comprising a shoe member, locking means on the shoe member, complementary locking means on the reciprocating member for engaging the first mentioned locking means, wedging means on one member and lever means carried by one of said members and adapted to engage the other member to force the members together whereby the wedging means moves the locking means into interlocking relationship.

6. A demountable rubbing means to be attached to the reciprocating member of a rubbing machine comprising a substantially rectangular shoe, a pair of parallelogram-shaped lugs upstanding from the shoe adjacent one end thereof, each of said lugs having two sides extending substantially diagonally of the axis of reciprocation of the shoe with the side toward the other end of the shoe having a wedge face, said lugs being adapted to fit into complementary slots on the reciprocating member, a plate defining an arcuate dovetail wedge-shaped recess at the other end of said shoe adapted to receive a complementary dovetail on the member, and engaging means on the shoe for engaging a clamp on the member to secure the shoe to the member to force the lugs into the slots and to wedge the dovetail into the recess.

7. A demountable rubbing means to be attached to the reciprocating member of a rubbing machine comprising a substantially rectangular shoe, a pair of parallelogram-shaped lugs upstanding from the shoe adjacent one end thereof, each of said lugs having two sides extending substantially diagonally of the axis of reciprocation of the shoe with the side toward the other end of the shoe having a wedge face, a plate defining an arcuate dovetail recess at said other end of the shoe, engaging means on the shoe for engaging a clamp on the member to secure the shoe to the member, and clamping means on the shoe for clamping a sheet of rubbing material thereto.

8. A demountable rubbing means to be attached to the reciprocating member of a rubbing machine comprising a substantially rectangular shoe, a pair of parallelogram-shaped lugs upstanding from the shoe adjacent one end thereof, each of said lugs having two sides extending substantially diagonally of the axis of reciprocation of the shoe with the side toward the other end of the shoe having a wedge face, a plate defining an arcuate dovetail recess at said other end of the shoe, and engaging means on the shoe for engaging a clamp on the member to force the lugs into the slots to secure the dovetail into the recess.

9. A demountable rubbing means for use with a rubbing machine having a reciprocating member comprising a substantially rectangular shoe, a lug on the shoe having a wedging face adapted to en-

gage the sides of a complementary slot on the member, an arcuate dovetail recess adjacent one end of the shoe and adapted to engage a complementary dovetail on the member and engaging means on the shoe for engaging a clamp on the member to force the lug into the slot and to secure the dovetail into the recess.

10. A demountable rubbing means for use with a rubbing machine having a reciprocatory member comprising a substantially rectangular shoe, a lug on the shoe having a wedging face adapted to engage the sides of a complementary slot on the member, a recess adjacent one end of the shoe and adapted to receive a complementary fit-

ting on the member, and engaging means on the shoe for engaging a clamp on the member to force the lug into the slot to wedge the fitting into the recess.
